FLYING BIRD TOY

Eugene E. Curtis, 708 S. Byrne Road, Toledo, Ohio

Filed Jan. 31, 1961, Ser. No. 63,773

Term of patent 14 years

(Cl. D34—15)

FIG. I is a bottom perspective view of a flying bird toy showing my new design, the side not shown being substantially similar to that shown; and

FIG. II is a top perspective view, the stick and line being omitted for convenience of illustration.

I claim:

The ornamental design for a flying bird toy, as shown and described.
